UNITED STATES PATENT OFFICE.

HENRY J. ABERNATHY, OF SOCORRO, TERRITORY OF NEW MEXICO.

UMBRELLA-SUPPORT FOR BICYCLES.

SPECIFICATION forming part of Letters Patent No. 611,190, dated September 20, 1898.

Application filed November 10, 1896. Serial No. 611,619. (No model.)

To all whom it may concern:

Be it known that I, HENRY J. ABERNATHY, a citizen of the United States, residing at Socorro, in the county of Socorro and Territory 5 of New Mexico, have invented certain new and useful Improvements in Bicycle Rests and Parasol-Holders; and I do hereby declare the following to be a full, clear, and exact description of the invention, such as will enable others skilled in the art to which it appertains to make and use the same.

This invention relates to improvements in bicycle attachments, and has more particular relation to bicycle canopies and rests.

15 Figure 1 of the drawings is a side elevation of a bicycle having my invention applied thereto, the canopy being raised, the dotted lines showing the device swung down to serve as a rest for the bicycle, the folded parallel 20 position not being shown, but evident from the construction. Fig. 2 is a perspective detail view showing the manner of hinging the supporting-rod to the clamp. Fig. 3 is a broken detail elevation, partly in section, illustrating 25 the manner of hinging the parts. Fig. 4 illustrates in detail the means for adjusting the canopy with relation to its staff.

A in the drawings represents the umbrella or parasol proper; B, the hollow supporting-rod; C, the staff telescoped within the same; D, the umbrella-supporting shank connected to the upper end of staff C; E, the attaching-clamp, and F the supporting-legs. The said 30 umbrella or parasol A is of any desired construction, but is preferably so mounted upon the shank D that when raised it is approximately horizontal, so as to present as little surface to the wind as possible. The upper end of said shank D is provided with a segmental plate G', forming two supporting-legs. The lower end of the shank D is provided 35 with a flat circular head d, having notches d' cut in its periphery. Said head d is pivotally mounted between the bifurcated upper end c of staff C by means of a pivot-pin c'. The upper portion of staff C is provided internally with a coil-spring c², engaging a sliding pawl c³ to normally force it up into engagement with one of the notches d' of the head d, so as to 40 hold said head d in any of its adjusted positions, thereby providing for the inclination of the umbrella or parasol A. The said pawl c³

is operated to disengage it from the said notches d' by a thumb-plate c⁴, connected to said pawl by a pin c⁵, passing through a slot c⁶, 55 formed in staff C. I preferably make the staff hollow, so as to reduce its weight. The staff C is adjustably mounted in the hollow support B by means of a clamping-screw b, passing through a vertical slot b', formed in 60 said support, and engaging a suitable screw-threaded aperture c⁷, formed in the staff. A suitable washer or plate b² is provided below the lower end of the clamping-screw b and is adapted to bear upon the side walls of the 65 slot b', so as to clamp said block firmly thereto when tightened.

The lower end of the support B is provided with a hinge member G, formed on a plate g, secured to the lower end of the support, the 70 hinge member being formed on its inner face with teeth g'. A similar hinge member g², having teeth g³ on its inner face and forming a part of what I term a "hinge-link" g⁷, contacts with said member G, a screw-threaded 75 stud g⁴ being secured in the member g² and projecting through an aperture in member G, so as to receive a suitable thumb-nut g⁵. A spiral spring g⁶ surrounds the stud g⁴ intermediate the hinge members, said members 80 being recessed to receive it, as clearly shown in Fig. 3, thereby tending to normally force the hinge members apart. It will be apparent that upon screwing up the thumb-nut g⁵ the two hinge members will be drawn together, so as to cause their teeth to interlock, 85 thereby rendering the parts rigid.

The lower end of the hinge-link g⁷ comprises a toothed hinged member g⁸, positioned at a right angle to the member g² at the upper end of the link, this member g⁸ coating with a similar hinge member H, formed on the clamp E, it being understood that the hinge formed by the members g⁸ and H is identical in construction and operation with 95 the hinge formed at the upper end of the hinge-link. The clamp E comprises a stationary segmental plate e and movable segmental plates e' and e'', hinged to said plate e. Said plate e is provided with a lip e³, having 100 a screw-threaded aperture e⁴. The said plate e² is provided with two spaced lips e⁵ e⁶. A binding-screw e⁶ engages the screw-threaded aperture e⁴ and is adapted to fit between the

lips e^5 and to incline thereon to clamp the plates e^1 and e^2 firmly about the backbone of the bicycle just forward of the saddle.

It will be observed from the foregoing description that I have provided for adjustment of the elevation of the canopy, of its inclination relative to the staff, of the inclination of the device relative to the bicycle when serving as a bicycle-rest, and for folding and carrying the device in a convenient position when not in use.

Having thus described my invention, what I claim as new, and desire to secure by Letters Patent, is—

15 1. The combination, with a clamp, a tubular supporting-rod, a two-hinged connection between the rod and clamp, a staff longitudinally movable in the supporting-rod, and a set-screw for securing the staff in the supporting-rod, the set-screw being secured to and movable with the staff, whereby it is adapted to serve as a handle for convenience in moving the staff.

20 2. The combination, with a clamp provided with a hinge member on its upper surface the plane of the face of which is at a right angle to the longitudinal axis of the clamp, of a tubular supporting-rod provided with a hinge member at its lower end, a hinge-link having

a hinge member at each end, adapted to co- 30 operate with the hinge members on the clamp and rod respectively to form hinges, set-screws for locking said hinges, and means for automatically forcing the hinge members apart when the set-screws are operated to release 35 the members, substantially as described.

3. The combination, with a clamp provided with a hinge member on its upper surface the plane of the face of which is at a right angle to the longitudinal axis of the clamp, of a 40 tubular supporting-rod provided with a hinge member at its lower end, a hinge-link having a hinge member at each end, adapted to co- operate with the hinge members on the clamp and rod respectively to form hinges, set-screws 45 for locking said hinges, and springs intermediate the members of each hinge for forcing said members apart when the set-screws are operated to release the members, substantially as described. 50

In testimony whereof I have signed this specification in the presence of two subscribing witnesses.

HENRY J. ABERNATHY.
